UNITED STATES PATENT OFFICE.

JOHN HENRY NYENHUIS, OF CHICAGO, ILLINOIS.

PADDLE WHEEL FOR BOATS AND THE LIKE.

Application filed June 24, 1918. Serial No. 241,494.

To all whom it may concern:

Be it known that I, JOHN H. NYENHUIS, a citizen of the United States, residing in Chicago, in the county of Cook and State 5 of Illinois, have invented a new and useful Improvement in Paddle Wheels for Boats and the like, of which the following is a specification.

This invention relates to paddle wheels 10 for boats and the like and has for its object broadly the provision of a paddle wheel of improved construction which will exert maximum propelling force.

I am aware that numerous paddle wheels 15 have been constructed and tested wherein pivoted blades are provided which are either permanently arranged in vertical position or at a given angle to the vertical. In order to obtain maximum efficiency I have discovered 20 that the blades should enter the water edgewise and leave it in the same fashion; and that also when projected edgewise the body of the blade should not interpose resistance to the water moving rearwardly 25 relatively as the boat advances. In other words, the blades should enter the water edgewise and inclined along the resultant path determined by the linear movement of the blade and the relative movement of the 30 water and the boat, and should leave the water in the same fashion. The blades on entering the water should each of them enter the water in slightly inclined position with respect to the vertical, while in the water 35 should swing to vertical position and leave the water with similar and opposite inclination. A paddle wheel so constructed not only does not interpose useless resistance to the propelling action but materially increases 40 the speed of movement of the blades while in the water in that they pass from an angle in advance of the vertical to an angle at its rear.

A further object of the invention is the 45 provision of a propeller of the paddle wheel type, which cannot become entangled with weeds and other obstructions in shallow streams and which cannot be damaged by encountering stones and other solid structure.

A further object of the invention is the provision of a paddle wheel having these 55 and other advantages, of simple and economic construction and from which delicate parts likely to require frequent repair or replacement are eliminated.

On the drawing,

Figure 1 is a transverse section through a paddle wheel embodying my present invention; and

Fig. 2 is a section taken substantially on the lines 2—2 of Fig. 1.

For the purpose of illustrating my present invention I have shown on the drawing diagrammatically a boat stern 11 rearwardly 65 from which extends a framework 12 provided with a rudder 13, the water line being indicated at 14. In bearings 15 a power shaft 16 is suitably positioned and driven through sprocket 10 and carries sprocket 70 wheels 17 at each side. Viewing Fig. 2 it will be noted that at each end of the shaft 16 is provided a short bearing shaft 18 from which arms 19 extend rearwardly and form bearings for a fixed bearing shaft 21. 75 Upon each shaft 21 and at its inner end is rotatably mounted a control member 22 upon the hub of which is provided a sprocket wheel 23 which is driven by a sprocket chain 24 from the sprocket wheel 17. The end 80 of the bearing shaft 21 beyond the member 22 is inclined downwardly and rearwardly at 25 to form a bearing at 26 for one side wheel or disc 27 forming the body of the paddle wheel. The bearings 21 and 26 at 85 each side are fixed bearings, that is to say they are fixed against movement in the ordinary operation of the paddle wheel and are only movable for purposes of adjustment and to prevent damage to the parts as will 90 be later more fully explained.

The two parts 27 constituting the body of the paddle wheel are each comprised of a central driving disc part 28, an outer peripheral or rim part 29 and connecting spokes 95 31. At intervals upon the rim 29 a plurality of bearings 32 are provided to pivotally receive the blades 33 which extend between the two body members. Each blade at each side is provided with a supporting 100 lever or arm 34 extending beyond the blade to a pivot part 35 which passes through the appropriate bearing 32 and therebeyond is extended in the form of an arm 36, the end of which at 37 is connected by a link 38 to 105 a pivot lug or short shaft 39 mounted in a bearing 41 upon the rim periphery 42 of the adjacent controlling member 22, which member is like the member 27 except that its rim 42 is of less diameter, the central 110 disc part 43 and the spokes 44 being like in substantially every respect the disc part 28

and the spokes 31 of its companion member 27.

A number of links 45 having outwardly extending bearing studs 46 at each end connect the two discs 28 and 43, one of the bearing studs having a rotatable bearing in each disc. There is thus independent driving connection between the body of the paddle wheel and the controlling members and between the blades of the paddle wheel and the controlling member. The parts are preferably so constructed that the blades enter and leave the water as indicated in Fig. 1. That is to say, they approach the water edgewise and inclined upon a line substantially the resultant of the speed of the boat and the travel of the propeller blades, this arrangement being permitted accurately by the construction shown on the drawing and described.

It will be manifest from the foregoing that the blade moving at an angle in advance of the vertical to an angle behind it while in the water has an accelerated movement and entering edgewise into the water along the resultant line of movement of the two parts and leaving the water in like fashion does not tend to churn the water or interpose resistance against the driving forces.

At each side a bar 51 of any suitable construction and having bearings at 52 upon a bearing shaft 21 extends upwardly and the bars at the two sides are connected by a cross member 53. This construction is for the purpose of adjusting the angularity of the blades and the bearing connections 52 are rigid with the shaft 21 so that if the frame consisting of the members 51 and 53 be swung rearwardly or forwardly the angularity of the portion 25 of the bearing shaft will be moved to alter the angularity of the blades. Above the rear of the scow or boat is provided a framework 54 and this framework carries a pin 55 adapted to engage in openings or perforations 56 in a regulating bar 57 which is pivotally connected at 58 with the frame composed of the members 51 and 53. The paddle wheel is supported by cables 59 fast in eyes 61 of upwardly extending side bars 51, which cables pass over pulleys 63 on frame upright 62 and about a ratchet held drum 64. When the paddle wheel engages a rigid obstruction its whole structure may be swung up, releasing the pull on the ropes thereby protecting it from damage, the wheel immediately returning to normal position after passing the obstruction.

It is thought that the invention and many of its attendant advantages will be understood from the foregoing description, and it will be apparent that various changes may be made in the form, construction and arrangement of the parts without departing from the spirit and scope of the invention

or sacrificing all of its material advantages, the form hereinbefore described being merely a preferred embodiment thereof.

I claim:

1. A paddle wheel for boats and the like, comprising a rotating body member, blades mounted thereon and continuously shifting in angular relation with respect to the radius between the center of said body member and the point of connection of each particular blade to said body member and continuously shifting also with respect to the vertical, and means for maintaining said blades in downwardly inclined position throughout their path of movement. 75

2. A paddle wheel for boats and the like, comprising a rotating body member and blades mounted on the periphery thereof, said blades being inclined always toward the water and, except when on vertical center, 85 at an angle with respect to the radius of the body member from the points of attachments of said blade and also with respect to the vertical.

3. A paddle wheel for boats and the like, comprising in combination a rotating body member, blades pivotally mounted about its periphery, the angularity of such blades shifting while in the water, and means for maintaining said blades in downwardly inclined position throughout their path of movement. 90

4. A paddle wheel for boats or the like, comprising in combination a rotating body member, blades pivotally mounted upon its periphery, an eccentrically mounted control member, and independent driving connections between said body member and the control member and between the control member and said blades, said latter connections serving also to secure said blades to said body member. 100

5. A paddle wheel for boats and the like, comprising in combination a rotating wheel at each side, a blade wheel eccentrically mounted with respect to said rotating wheels, levers offset with respect to the plane of and pivoted at their centers with said blade wheel, blades lying along the arms of said levers, the other arms of said levers 110 being pivoted to said rotating wheels. 115

6. A paddle wheel for boats and the like, comprising in combination a rotating wheel at each side, a body wheel eccentrically mounted with respect to said rotating 120 wheels, levers pivoted in said body wheel, links connecting said levers with said rotating wheels, and blades carried by said levers and located at a side of the pivotal axis thereof. 125

7. A paddle wheel for boats and the like, comprising in combination a rotating wheel at each side, a body wheel eccentrically mounted with respect to said rotating 130 wheels, levers pivoted in said body wheel,

links connecting said levers with said rotating wheels, blades carried by said levers and located at a side of the pivotal axis thereof and lying substantially in the plane of connected levers.

8. A paddle wheel for boats or the like, comprising a body member, blades on said

body member, a control member eccentrically mounted with respect to said body member and having connection with said blades 10 and support for said body member yieldable in an upward direction only.

JOHN HENRY NYENHUIS.
